UNITED STATES PATENT OFFICE

143,142

DESIGN FOR WRITING PAPER OR THE LIKE

Milan Freund and Paul Neuberger,
New York, N. Y.

Application August 7, 1945, Serial No. 121,301

Term of patent 7 years

(Cl. D59—14)

To all whom it may concern:

Be it known that we, Milan Freund and Paul Neuberger, citizens of the United States and Yugoslavia, respectively, residing in New York, county of New York, and State of New York, have invented a new, original, and ornamental Design for Writing Paper or the like, of which the following is a specification, reference being had to the accompanying drawing, in which the figure is a front view of a sheet of writing paper showing our new design.

We claim:

The ornamental design for writing paper or the like, as shown.

MILAN FREUND.
PAUL NEUBERGER.
